UNITED STATES PATENT OFFICE.

FREDERICK E. MARTIN, OF WEED, CALIFORNIA, ASSIGNOR TO MARTIN AIR DOG COMPANY, OF SAN FRANCISCO, CALIFORNIA, A CORPORATION OF CALIFORNIA.

LINK DOG FOR SAWMILL CARRIAGES.

Original application filed November 25, 1921, Serial No. 517,647. Divided and this application filed November 23, 1922, Serial No. 604,062. Renewed May 4, 1926.

This invention is directed to dogging means for use in connection with saw mill carriages.

It is well known that the logs on saw mill carriages have a tendency toward endwise movement, notwithstanding the dogs heretofore employed under the sudden stopping of the carriage in its return movement, this tendency particularly in heavy logs being at 10 times sufficient to distort the usual holding dogs.

The present invention is directed broadly to means designed to overcome this tendency of the log to endwise movement, with such 15 means designed to engage the underside of the log, preferably between the knees, with such dogging means having an effective range between the line of the knees and the line of operation of the saw.

More specifically, the invention relates to 20 a saw mill dog or dogs mounted and positioned on the carriage to engage the underside of a log in advance of the knee line, with such dog or dogs operable at will to 25 bite into the underside of the log to prevent it moving endwise following or during carriage movement, and to this specific extent this application is in part a division of my co-pending application filed November 25, 30 1921, Serial No. 517,647.

It is further important in an under log dogging means that it be capable of cooperation with the log in all positions of the knees and yet not project beyond the saw line to interfere with the operation of the saw, and as the knees and therefore the log must be adjusted on the carriage during the successive sawing operations, the desirable 35 type of under log dogging means must be capable of movement at the time the knees are moved, to maintain an effective engagement with the underside of the log in all positions of the knees.

Therefore, the present invention further 40 comprehends an under log dogging means, which are advanced or retracted at the time the knee or knees is or are moved for the adjustment of the log, with such dogging means prevented from extending over the saw line in any operative position thereof.

The invention, in the preferred and modified forms of construction, is illustrated in the accompanying drawings, in which;

Fig. 1 is a plan view showing conventionally a saw mill carriage having the improved under log dogging means connected therewith. 55

Fig. 2 is a side elevation illustrating more particularly the relation of the under log dogging means and carriage, and showing 60 the means for operating the under log dogging means.

Fig. 3 is a perspective view of the under log dogging means.

Fig. 4 is a transverse section of the same. 65

Fig. 5 is a perspective view of one of the links of said dogging means.

Fig. 6 is a longitudinal section of a slightly modified form of under log dogging means. 70

Fig. 7 is a perspective view of another form of under log dogging means.

A saw mill carriage 1 is here conventionally shown, having knees 2 provided with the usual dogs 3 for engaging the log. The 75 under log dogging means of the present invention comprises a frame 4 mounted at its rear end upon a pivot pin 5, supported in a bracket 6, which in turn is secured to and supported on one of the intermediate rails 7 80 of the carriage. The frame 4 extends forwardly from the carriage in a plane in parallelism with the knees, and terminates at its forward end inwardly of the saw line relative to the carriage. The frame is preferably mounted on the carriage at a point between the knees, but no limitation is intended in this application either with regard to the specific location of the under log dogging means, or as to the number of such 85 means as may be employed in connection with any particular carriage.

The frame 4 comprises spaced parallel side plates 8, the extreme upper edges of which are formed to present a biting edge 9, and the extreme forward upper ends of which present engaging or biting projections 10. The inner surfaces of the plates 8 are formed with longitudinal channels 11, and a division plate 12 seated at its edges 95 in these channels and having the side plates 8 secured thereto as at 13, provides for maintaining these side plates in proper spaced frame-forming relation and at the same time 100 divides the channels 11 into upper and lower 105 grooves 14 which extend throughout the

length of the division plate, and around the ends thereof.

The dogs proper are carried by and arranged for movement in the frame 4, such comprising an endless series of movably connected links 15, having lateral rollers 16 to seat in the grooves 14 and guide such links in their movement in the frame 4. Certain of the links 15 are provided with upstanding dogs 17, preferably arranged in pairs with their extreme upper ends formed for biting engagement with the log. It will of course be understood that the dogs proper are thus designed for travel in an endless path within the plane of the frame 4, and that the uppermost dogs, at the particular moment of operation, are the ones that will engage the underside of a log. In this connection and with particular reference to Fig. 4, it will be noted that the dogs 17, when in operative position, project some distance above the biting edges 9 of the frame side plates 8, to thereby provide two distinct and effective ranges for the under dogging means, as will be hereinafter pointed out.

From the above description, it will be apparent that the frame 4 is designed for a pivotal or up and down swinging movement with respect to the carriage, that is, with respect to a log, while the dogs proper are capable of a free travel in an endless defined path within such frame, with this line of travel substantially at right angles to or generally across a log on the carriage. The swinging movement of the frame is designed for and utilized to force the dogs into biting cooperation with the log, while the independent movement of the dogs proper is designed to compensate for the adjustment of the log on the carriage through movement of the knees. Therefore, the operation of the frame to cause the dogs to bite into the log should be capable of manual control at will, while the compensatory and independent movements of the dogs proper should be more or less automatically taken care of at the time the knees are moved.

To provide for operating the frame 4 and therefore causing the dogs and frame edges 9 to bite into the log, links 18 depend from the frame and are connected by a crank arm 19 to a shaft 20 suitably mounted below the forward portion of the carriage. A second crank arm 21 projects from the shaft 20 and is connected to a piston rod 22 having a piston 23 operating in a cylinder 24. The cylinder is formed with appropriate ports for the admission and relief of fluid (preferably air) under pressure, whereby through obvious movement of the piston 23 in one direction or the other, the dog frame 4 will be moved upwardly or downwardly on its pivotal support 5.

As the dogs proper must have the com-

pensatory movement referred to, and this movement is one more or less dependent upon the movement of the knees in adjusting the log, it is apparent that this compensatory movement of the dogs should take place at the time the knees are moved, and may, if desired, be controlled directly in the movement of the knees. For example, as a means of carrying out this movement, one or more of the links 15 may be provided with a bar extension 25 movably connected to a rod 26, which latter extends from one or the other of the knees. Thus, as the knee with which the dogs are connected is moved, the dogs are correspondingly moved in the frame 4, and hence a desired relation is maintained between the knees and dogs. It is of course apparent to any one skilled in this art that the dogs need not be moved directly by the knees in order to provide the compensatory movement referred to, as the dog moving element may be operated directly from the usual set shaft, by any preferred type of gearing or connections, and under these circumstances the compensatory movement of the dogs will still be in desired relation to the movement of the knees.

In the operation of the preferred form, after the log is in position, pressure is admitted to the cylinder 24 to rock the shaft 20 and move the crank arm 19 in the direction of the arrow, Fig. 3, whereupon the frame 4 is moved upwardly to cause the dogs to bite into the log. If the bark on the log is thick, or the log unusually heavy, the dog 17 will pass through the bark and into the more solid part of the wood structure, while the biting edges 9 of the side plates 8 penetrate the bark to a greater or less degree. The log is thus positively held against endwise movement relative to the carriage by two distinctive dog holding elements, each having its own penetrating depth, and these penetrating depths being at different levels. Under ordinary circumstances, that is, with ordinary logs, the frame is so operated that the dogs 17 alone penetrate the log for holding purposes, but where the log is unusually heavy, or the bark on the log unusually thick, advantage is taken of both the biting edges 9 and the dogs 17, as were the dogs alone used, the penetration might not be entirely through the heavy bark on the log, and hence the log would not be effectively secured.

After the log is engaged with the under log dogging means as described, and the knees are subsequently adjusted, either to meet ordinary sawing conditions or for tapering the log, the dog links 15 are moved at the time the knee is moved and in a similar direction to more or less compensate for this log movement, without interfering with the relation between the log and under log dogging means, either in its

biting cooperation, or in a subsequent movement of the under log dogging means for such biting cooperation. In this movement of the dogs proper in the frame 4, it will be apparent that at no time can the dogs reach a position across the saw line, for the dogs are compelled to travel in a predetermined path in the frame, and this path terminates short of the saw line.

10 In the preferred form described, the dogs proper are positively moved at the time the knee is moved; and while this construction is advantageous to meet all logging conditions, yet nevertheless under some such 15 conditions the dogs may be left free and moved only through and by the movement of the logs as the knees are adjusted. Such a construction is illustrated more particularly in Fig. 6, where the frame 4 is 20 similar to that described in the preferred form and is designed to be operated in the same or a similar manner. The dogs of this preferred form however, are shown at 27 as projecting from the links 28 of an endless 25 chain 29 adapted to travel in the grooves 30 in the side plates of the frame 4 which correspond to the grooves 14 of the preferred form. Here, as the log is moved under the adjustment of the knees, the dogs 27, by 30 reason of the freedom of movement of the chain 29, follow the log, thus effectively maintaining a dogging means which automatically compensates for the adjustment of the log, without however, having any fixed 35 means for operating the dogs proper to provide such compensation. The continuous chain in this modified form is obviously moved by the log in one direction only, for when the under dogging means is withdrawn 40 from the log, and the knees returned to normal position, the dogs remain stationary. However, this is no disadvantage in the effective operation of this type for the dogs are arranged in endless formation, 45 under which circumstances a certain proportion of the dogs will be at all times in position to engage a log when the frame 4 is operated.

50 A further modified form of the invention is shown in Fig. 7, in which form the independently movable dogs are dispensed with, and the dog compensation for log movement provided for in a different manner. In this form, the dogging means comprises a bar or plate 31 pivotally supported at 32 upon a bracket 33, corresponding to the bracket 6 of the preferred form, the bar 31 being operated by links 34, connected to the crank arm 19 of the preferred means of 55 operation. Thus the bar 31 is in effect the same as the original frame 4. The upper edge of this bar is sharpened to a biting edge 35, and such edge is undulating lengthwise the same as indicated at 36. The terminal of the edge has the biting projection

37 corresponding to the projection 10 of the preferred form. In the operation of this modified form, the biting edge 35 is forced into the log to hold the same against relative endwise movement, exactly as are the 70 dogs of the preferred form. In the movement of the log however, in the adjustment of the knees, compensation between the under dogging means of this form and the log is permitted to the undulating biting 75 edge of this dogging member, which permits the log to roll or move over such biting edge without separating such edge from the log. Thus, as in the preferred form, the movement of the log is compensated for 80 without disturbing the biting cooperation of the dogging means with the log.

I have stated that the link dogs may be operated from the set shaft or from or in connection with the setting mechanism. For 85 reasons which may arise in practice, it may be found advisable to have the link dogs move at a slightly different speed than that of the knee, and in order to meet this condition, the necessary means to accomplish it 90 can very readily be operated by the setting mechanism. Therefore, it is to be understood that where the phrase occurs "moved in unison with the knee" or "timed to move with the knee" contemplates movement of 95 the dogs at the same speed as or at a different speed from that of the knee.

Great difficulty and loss is experienced in sawing logs through the logs slipping or shifting endwise on the carriage. This action is due to the momentum of the log in the reciprocal movement of the carriage, and when it occurs, it frequently bends the knee dogs or disengages them from the log and throws the latter out of alignment with the 100 knees and the saw line. Because of the irregular shape of the ends of many logs, they roll on the carriage when the knee dogs become disengaged, hence the log is liable to 105 assume any but the position determined by 110 the setter. In many instances, the shifting of the alignment of a log is not great enough to be noticeable to the setter or sawyer, and herein lies one of the essential reasons why a log should be positively held up against 115 the knees.

I have discovered that by dogging a log on its underside, and arrange these dogs to take hold in the same relation to the knees in their movement on the blocks, endwise movement or slipping is prevented, and at the same time the bite of the dogs in the log holds it against rolling, which materially increases production and improves the grade 120 of lumber.

125 While not absolutely essential, I have also discovered that if link or similar dogs are located at a point or points between the usual knee dogs, a surprising result is obtained in handling certain kinds of logs.

The usual knee dogs when used alone grip a log in such a manner that the weight of the log always tends to pull or roll the log away from the dogs. By placing dogs at a point between knee dogs to engage the lower surface of the log where the whole weight of the log is supported on the dogs, the tendency of the log to roll is overcome, hence the unequal distribution of the weight in various parts of the log, which more or less causes it to roll and break away from the knee dogs, is prevented. That is to say, the link dogs insure against slipping, thus, once a log is held by the knee and link dogs, its position is fixed against the knees and a predetermined saw line is maintained.

From the description of the construction and operation, it will be seen that I have provided means to effectually overcome the difficulties heretofore outlined, and that the means so provided will positively hold a log in set position on a carriage.

It is to be understood that while I have illustrated and described the frame 4 as mounted for a swinging movement relative to the carriage, this particular type of movement is not necessarily essential to the proper operation of the dogs, as the frame may, with equal facility, and by simple mechanical changes not necessary to illustrate, be made to slide bodily up and down in order to force the dogs into cooperation with the log or withdraw the same. Therefore, the swinging movement of the dog frame herein described and illustrated is intended and designed to cover any movement of the dog frame by which the dogs may be forced into and withdrawn from the log.

Furthermore, the dog frame is here described as operated from a pressure cylinder through intermediate rod and link connections. This illustration is merely for convenience in locating the parts, as it will be understood that the piston of the cylinder may be connected directly to the frame, and the cylinder located directly below the frame, so that the latter may be operated, so to speak, directly from the cylinder, without the use of intermediate connections.

50 What I claim is:

1. In combination with a saw mill carriage, knees thereon, dogs associated with each knee, and means including a dog having a support upon the carriage independent of the knees and located between the knees and extending across the path of the underside of a log and adapted to engage the latter, means to cause the dog to move with the knee, and means for actuating the dog to engage the underside of the log and against its own weight.

2. In combination with a saw mill carriage, knees, dogs mounted to move with the knees and located in advance of the same to engage the bottom of a log, said

dogs having a support upon the carriage independent of the knees and operated to engage the log through movement of such mounting, and means for operating the dogs.

3. In combination with a saw mill carriage, knees mounted thereon, a dog frame mounted on the carriage independent of the knees and extending across the path of a log when supported on said carriage, dogs mounted in the frame means for moving the dogs to engage the bottom of a log when up against the knees, and means to cause the knees and the dogs to move together when setting a log.

4. In combination with a saw mill carriage, knees mounted thereon, a frame mounted independently of the knees, a plurality of dogs mounted in the frame and movable with the knees, and means for operating the dogs to cause same to engage a log.

5. The combination with a saw mill carriage, knees, a dog frame movably mounted on the carriage, a plurality of connected links operable and guided in the dog frame, certain of the links having dogs extending therefrom to engage a log, means to cause the links to move in the dog frame at the time a knee is moved, fluid pressure means for actuating the dog frame to cause the dogs to engage a log, and means for controlling the action of the fluid pressure means.

6. In combination, a saw mill carriage, knees thereon, a dog having a support upon the carriage independent of the knees and movable in advance of the knees and at the time the knees move and normally out of the path of the bottom of a log supported on the carriage, and means on the carriage for actuating the dog in any position of the knees to engage the underside of a log.

7. In combination, a saw mill carriage, a knee movable thereon, a flexible series of dogs movable with and in advance of the knee, means on the carriage independent of the knee for supporting and guiding the dogs and preventing the said dogs extending over the path of movement of the saw, and means on the carriage for actuating the dogs to engage a log.

8. In combination, a saw mill carriage, a knee movable thereon, a dog carrier mounted on the carriage, flexibly connected dogs movable in the carrier, a connection between the dogs and knee, and means for operating the carrier to actuate the dogs with respect to a log, said carrier being formed to maintain a predetermined path of travel of the dogs in the movement of the knee.

9. In combination, a saw mill carriage, a knee movable thereon, a dog carrier mounted on the carriage, flexibly connected dogs movable in the carrier, a connection to cause the dogs to move with the knee, and means for

- operating the carrier to actuate the dogs with respect to a log, said carrier being formed to maintain a predetermined path of travel of the dogs in the movement of the knee and to limit this path of travel inwardly of the path of movement of the saw.
10. In combination, a saw mill carriage, a knee, a movable dog having a support upon the carriage independent of the knee and extending in the path of a log to be operated upon and movable at the time the knee is moved, and means for operating the dog to engage a log.
11. In combination with a saw mill carriage, a knee thereon, a dog mounted on the carriage and having a support upon said carriage independent of the knee and extending across the path of a log, and means to cause movement of the dog at the time of movement of the knee.
12. In combination with a saw mill carriage, a knee, a dog mounted on the carriage and having a support upon said carriage independent of the knee, means for causing the dog to move across the path of a log at the time the knee is moved, and means for operating the dog to engage a log.
13. In combination with a saw mill carriage, knees on the carriage, a dog having a support upon the carriage independent of the knees and extending across the path of a log in advance of the knees, said dog having log engaging elements at different levels, means for causing certain of the log engaging elements to move across the line of the log at the time one of the knees is moved while others maintain their original position, and means for actuating the dog to engage a log.
14. In a saw mill carriage, an under log dogger, comprising dogging means for engagement with the log when the latter is against the knees in position for sawing, and at all times effective throughout the full adjustment range of the knees and movable into and out of engagement with the under surface of the log and having an independent movement to compensate for log adjustment by the knees.
15. In a saw mill carriage, an under log dogger, comprising dogging means for engagement with the log when the latter is against the knees in position for sawing, and adapted for swinging movement relative to the carriage to and from biting engagement with the log, said dogging means having a support upon the carriage independent of the knees and having an independent movement to compensate for log adjustment by the knees.
16. In a saw mill carriage, the combination with an under log dogger, comprising dogging means arranged beneath and transverse the log position on the carriage for engagement with the log when the latter is against the knees in position for sawing, said dogging means having an effective range throughout the full adjustment of the knees, of means for moving the dogging means relative to the log for dogging the same, and means to permit an independent movement of the dogging means to compensate for the log adjustment by the knees.
17. The combination with a saw mill carriage of an under log dogger for engagement with the log when the latter is against the knees in position for sawing, and movable to and from the log for dogging purposes, and having a dogging range for substantially the full distance intermediate the saw line and the retracted positions of the knees, said dogging means having an independent movement to compensate for the movement of the log under any adjustment.
18. The combination with a saw mill carriage of an under log dogger for engagement with the log when the latter is against the knees in position for sawing, comprising dogging means mounted for movement relative to the carriage and having an effective range for dogging purposes substantially equal at all times to the distance between the saw line and the fully retracted positions of the knees, said dogging means permitting independent movement of the log under any adjustment without interfering with the bite of the dogging means.
19. The combination with a saw mill carriage of a plurality of interconnected dogs mounted on the carriage and independent of the knees and operative in a substantially straight line under a log on the carriage, means to operate the plurality of interconnected dogs for biting operation with respect to the log, and means to operate the plurality of interconnected dogs at the time the knees are moved for log adjustment to maintain the dogging action without regard to the log movement under such knee adjustment.
20. An under log dogger for saw mill carriages, comprising a plurality of inter-connected dogs mounted on the carriage and operative in a substantially straight line under a log positioned on the carriage, said plurality of inter-connected dogs being adapted for movement to and from the log position for dogging operation and independently movable with the log after dogging operation in those movements of the log responsive to knee adjustment.
21. An under log dogger mounted to swing on the carriage independently of the knees, said dogging means being further mounted for bodily movement toward and from the saw line concurrently with the adjustment of the knees.
22. An under log dogger mounted to swing on the carriage independently of the knees

- 5 said dogging means being further mounted for bodily movement toward and from the saw line concurrently with the adjustment of the knees, said bodily movement of the dogging means being effective to engage the underside of a log at all times for the entire distance between the saw line and the face of the knees.
- 10 23. The combination with a saw mill carriage, of an under log dogger for engagement with a log when the latter is against the knees in position for sawing, and operative to and from the log, said dogger being mounted for an independent movement to
- 15 maintain the dogger in biting engagement with the log during adjustments of the log by the knee, said dogger being effective at all times for the entire distance between the saw line and face of the knee.
- 20 24. An under log dogger for engagement with a log when the latter is against the knees in position for sawing having dogging means movable to and from the log for dogging action, said dogger including an additional dogging means relatively movable to compensate for log adjustment by the knees, said additional dogging means having a permanent path of travel equaling at least the full possible adjustment
- 25 range of the knee.
- 30 25. An under log dogger for engagement with a log when the latter is against the knees in position for sawing having dogging means movable to and from the log for dogging action, said dogger including an additional dogging means relatively movable to compensate for log adjustment by the knees, said respective dogging means having varying penetrating depths in dogging action.
- 35 26. An under log dogger having independent dogging means arranged transverse the position of the log on the carriage, means for swinging both said dogging means for dogging engagement with the log, and means for operating one of said dogging means at the time the knee is adjusted to compensate for resultant log movement.
- 40 27. An under log dogger having independent dogging means arranged transverse the position of the log on the carriage, means for swinging both said dogging means for dogging engagement with the log, and means for operating one of said dogging means at the time the knee is adjusted to compensate for resultant log movement, both said dogging means being effective for the full range from the retracted position of the knee to the saw line.
- 45 28. A dogging means, comprising a frame supported on a saw mill carriage below a log for movement toward and from the log to be dogged when against the knees, and a plurality of dogs movable with and in said frame.
- 50 29. A dogging means, comprising a frame supported on a saw mill carriage below a log for movement toward and from the log to be dogged when against the knees, and a plurality of dogs movable with and in said frame.
- 55 30. A dogging means, comprising a frame supported on a saw mill carriage below a log for movement toward and from the log to be dogged when against the knees, and a plurality of dogs movable with and having a predetermined path of travel in said frame.
- 60 31. A dogging means, comprising a frame supported on a saw mill carriage below a log for movement toward and from the log to be dogged when against the knees, and a plurality of dogs movable with and having a predetermined path of travel in said frame, said path of travel being defined by and within the limits of the frame.
- 65 32. A dogging means, comprising a frame supported on a sawmill carriage below a log for movement toward and from the log to be dogged when against the knees, and a plurality of dogs movable with and in said frame, said dogs projecting above the frame for dogging operation.
- 70 33. A dogging means, comprising a frame, having integral dogging edges, and a plurality of independent dogs movable with and in said frame.
- 75 34. A dogging means, comprising a frame, having dogging edges, and independent dogs movable in said frame, the operative ends of the dogs extending beyond the dogging edges of the frame.
- 80 35. A dogging means, comprising a frame supported on a saw mill carriage below a log for movement toward and from the log to be dogged when against the knees, said frame, having guideways, and a plurality of dogs freely slid able in said guideways.
- 85 36. A dogging means, comprising a frame supported on a saw mill carriage below a log for movement toward and from the log to be dogged when against the knees, said frame having spaced side bars formed with guideways, and a plurality of connected dogs freely slid able in said guideways.
- 90 37. A dogging means, comprising a frame supported on a saw mill carriage below a log for movement toward and from the log to be dogged when against the knees, said frame being formed with guideways, and a plurality of connected dogs freely slid able in said guideways, said guideways limiting the movement of the dogs to within the length of the frame.
- 95 38. In combination with a saw mill carriage, knees, dogs mounted to move with the knees and located in advance of the same to engage the bottom of a log, said dogs having pivotal connection with the carriage independent of the knees and operated to

engage the log through movement on said pivotal connection, and means for operating the dogs.

39. In combination with a saw mill carriage, knees mounted thereon, a dog frame pivoted on the carriage and extending across the path of a log when supported on the carriage, dogs slidably mounted in the frame, and means for tilting the frame on its pivot to cause the dogs to engage in the bottom of the log when up against the knees to prevent lengthwise movement of the log.

40. In combination with a saw mill carriage, knees mounted thereon, a dog frame pivoted on the carriage and extending across the path of a log when supported on the carriage, dogs slidably mounted in the frame, means for tilting the frame on its pivot to cause the dogs to engage in the bottom of a log when up against the knees

to prevent lengthwise movement of the log, and means to cause the knees and the dogs to move together on the carriage when setting a log.

41. A saw mill carriage, knees thereon, 25 an under log dogger comprising a frame mounted on the carriage independently of the knees and extending substantially transverse the length of a log from a normal knee position to a position short of the saw line 30 and movable toward and from the log and provided with log engaging means, and means whereby said frame may be operated to cause said engaging means to engage the underside of a log to hold said log against 35 endwise movement notwithstanding the movement of the log toward the saw line through movement of the knees.

In testimony whereof I affix my signature.
FREDERICK E. MARTIN.
